W. T. BEATTY

COMBINATION GRADER MAINTAINER BLADE FOR ROAD MACHINES

Filed July 2, 1923

Fig. 1.

Patented July 15, 1924.

1,501,262

UNITED STATES PATENT OFFICE.

WILLIAM T. BEATTY, OF FLOSSMOOR, ILLINOIS.

COMBINATION GRADER-MAINTAINER BLADE FOR ROAD MACHINES.

Application filed July 2, 1923. Serial No. 649,045.

To all whom it may concern:

Be it known that I, WILLIAM T. BEATTY, a citizen of the United States, residing at Flossmoor, in the county of Cook and State 5 of Illinois, have invented a certain new and useful Improvement in Combination Grader-Maintainer Blades for Road Machines, of which the following is a specification.

10 This invention relates to many conventional road maintainer machines, tractors, rollers, and others. In maintenance work, it is desirable to have a relatively narrow maintainer blade, carried by the machine, 15 pass over the surface of the ground or road, scraping off surface irregularities thereon, the dirt or other material so scraped sliding or dribbling over the top of the maintainer blade back onto the road itself. When, as 20 shown in the drawings, the device is applied to a roller, the dirt is subsequently pressed down into place by the roller. In such work, it is also desirable to have a substantially higher blade which may and may 25 not cut the surface of the road for scraping substantial quantities of dirt on the surface of the road to the side thereof, or from the side to the center of the road, depending whether the particular machine is 30 engaged in flattening or crowning the road. The object of this invention is to provide such scraper use and which can be adjusted 35 to various predetermined, angular positions between said two extreme positions, thereby, in the construction of a given road machine, doing away with the expense of providing 40 two separate and distinct blades for the two purposes.

The invention consists in mechanism capable of attaining the foregoing and other objects, which can be comparatively easily 45 and cheaply made, which is satisfactory in use and is not readily liable to get out of order. It further consists in numerous features and details of construction which will be hereafter more fully set forth in the specification and claims.

Referring to the drawings in which like numerals designate the same parts throughout the several views:

Figure 1 is a side elevation of the mechanism of this invention applied to one of many forms of road working tools which

can make use of the device, specifically, to the roller-maintainer of Beatty, Davis, Wilson prior application, Serial Number 610, 60 345.

Figure 2 is a rear view of the blade mechanism of this invention taken on the line 2—2 of Figure 1.

Figure 3 is an enlarged end view of the device as it appears in Figure 1, taken on 65 the line 3—3 of Figure 2.

Figure 4 is an enlarged rear view taken from the right hand side of Figure 3, the hinge mechanism 53 and bracket 18 being omitted.

The roller maintainer mechanism, to which this invention is here shown applied, comprises an engine carrying body mechanism 10, sustained on rear wheels 12 and a front wheel 14 about which is arranged in 70 front of the machine a plurality of runners 16 carrying at their front ends brackets 18 to which the working blade 20 is attached by any suitable means not entering into this invention. The lower blade 20 here shown 75 as a metallic right-angled member, with or without a separate, sharpened cutting member 22, detachably secured in place by bolts 24, has its upper flange 26 resting on brackets 18. The upper section of the complete 80 blade mechanism of this invention is an elongated board or plate 32, arranged above and parallel with the upper edge of blade 20, as shown in the drawings, the blade 20 and the plate 32 being pivotally secured 85 together by a plurality of hinges 34, each having one leaf 35 secured to the flange 26 by any suitable means, as rivets 36, while the other leaf 37 is secured to the plate 32 by any suitable means, such as rivets 38. 90 Loosely and pivotally mounted near the outer or free swinging edge of the plate 32 on or adjacent to each hinge, specifically in 95 a hook 40 on the adjacent hinge leaf 37, is a brace or locking rod 42, having a horizontally turned end 44 adapted to be selectively 100 inserted in different ones of a plurality of laterally spaced holes 45—46—47 in a lug 48 rising from the adjacent lower hinge leaf.

With the mechanism just described, the 105 operator can assemble the device as shown in Figure 3 with the member 44 in hole 46 with the result that the blade 20 and the plate 32 make a combined scraper blade having a slight angularity or curvature on its 110 working face. When the operator moves member 44 from perforation 46 to perfora-

tion 45, plate 32 is swung in a counter-clockwise direction from that viewed in Figure 3 to increase this curvature of the working face. When, on the other hand, 5 the operator rocks plate 32 in a clockwise direction about pivots 34 until member 44 enters perforation 47, the plate 32 is inclined considerably away from the work with the result that some of the material cut 10 from the road by the member 22 can pass up over plate 32 as in ordinary maintaining operation. When member 44 is wholly disengaged from lug 48, and the plate is allowed to assume the dotted line or final position 15 of Figure 3, the plate 32 only slightly obstructs the top of blade 20 and earth in front of, i. e., to the left of, blade 20, freed by it, passes over the device in ordinary maintainer operation fashion.

20 From the foregoing, it will be seen that by the use of the principles of this invention, the plate 32 may be in its operation rendered adjustable to any angular position desired above the blade 20.

25 The prior application, above referred to, illustrates and claims a maintainer blade in which the extension ends or wings 50 and 52 are provided, carried on hinges 53 and 55 which permit these extensions to assume the position shown in Fig. 2, where the blade is lengthened, and positions at 180° therefrom in which the blade ends point toward the center of the main blade and not only leave it of normal length but are out of the way in 30 its work. In Figure 2, these extension ends 50 and 52 are shown the same height as the principal or center blade 20—22, heretofore described, and as equipped with extension plate members 54 and 56 aligning with plate 32, each said plate extension being hinged to its adjacent blade member 50 or 52, as the case may be, by adjustable hinge devices 58, identical in detail with the disclosure of Figures 3 and 4, heretofore described. The 35 result of the construction shown in Figure 2 is that the operator can lengthen or shorten the main blade mechanism and secure the desired adjustments in the extension portions as well as in the main portion 40 of the blade device.

When a machine of the class described is equipped with the blade mechanism of this invention, the operator can use it with the plate 32 elevated as an ordinary scraper and, 45 on lowering the plate into the dotted line position of Figure 3, use it as an ordinary maintainer. He can secure intermediate desired positions by shifting the member 44 into the various holes 45—47.

50 Having thus described my invention, what I claim as new and desire to secure by Letters Patent is:

1. In mechanism of the class described, a normally upright blade for ground engagement, a plate hinged adjacent to the

upper edge thereof and means for locking the plate in a plurality of selected angular positions with reference to the blade.

2. A device of the class described, comprising two parallel, elongated members of 70 substantial width hinged together, one of said members being equipped for engagement with ground to be worked, and means for detachably securing said members in selected, angular positions with reference 75 to each other.

3. A device of the class described, comprising a normally upright working blade, a plate parallel thereto above it, a hinge connection between the blade and plate permitting them to selectively lie in the same plane or with the plate at about right angles to the blade, and means for detachably locking the plate in the first mentioned position.

4. A device of the class described, comprising a normally upright working blade, a plate parallel thereto above it, a hinge connection between the blade and plate permitting them to selectively lie in the same plane or with the plate at about right 80 angles to the blade, means for detachably locking the plate in the first mentioned position and at other slightly different angles.

5. In mechanism of the class described, a comparatively low working blade, means for operatively supporting it on a traveling machine, a plate above the blade, means hinging the blade and plate, means detachably locking the plate in selected angular positions, forward of the blade, in the plane 95 of the blade, and behind the blade, and means in the hinge permitting the plate to swing back to a point where it is substantially out of the way of earth passing horizontally over the top of the blade.

6. In mechanism of the class described, a comparatively low working blade, means for operatively supporting it on a traveling machine, a plate above the blade, means hinging the blade and plate, means detachably 100 locking the plate in selected angular positions, forward of the blade, in the plane of the blade, and behind the blade, and means in the hinge permitting the plate to swing back to a point where it is substantially out 105 of the way of earth passing horizontally over the top of the blade, a supplemental blade capable of use to extend the length of the main blade, said supplemental blade carrying a corresponding hinged upper 110 plate, aligning with the first plate when the blade is extended.

7. In mechanism of the class described, a blade having two removable end extension members, a plate above each blade member, a hinge between each blade member and its plate, and means for fastening each plate in selected angular position on its blade member.

8. In mechanism of the class described, 110

an angle member having one flange face substantially vertical, forming an earth working element, the other flange being at the top and approximately horizontal, a plurality of hinges along the top flange, an earth working plate, normally parallel to the first face of the angle carried by said hinges and brace rods carried by one of the two members which are hinged together detachably engaging different fixed points on the other.

9. In mechanism of the class described, an angle member having one flange face substantially vertical, forming an earth working element, the other flange being at the top and approximately horizontal, a plurality of hinges along the top flange, an earth working plate, normally parallel to the first face of the angle carried by said 15 hinges and brace rods carried by the swinging plate adjacent to the hinges selectively

interlockable with different points on the hinge part which is attached to the angle member, for the purposes set forth.

10. In mechanism of the class described, 25 an angle member having one flange face substantially vertical, forming an earth working element, the other flange being at the top and approximately horizontal, a plurality of hinges along the top flange, an earth working plate, normally parallel to the first face of the angle carried by said 30 hinges and brace rods carried by the swinging plate adjacent to the hinges selectively interlockable in holes prepared for it at different points on the hinge part which is attached to the angle member, for the purposes set forth.

In witness whereof, I have hereunto subscribed my name.

WILLIAM T. BEATTY.
